UNITED STATES PATENT OFFICE.

PAUL M. HENGSTENBERG, OF WILKINSBURG, PENNSYLVANIA, ASSIGNEE TO WESTINGHOUSE ELECTRIC & MANUFACTURING COMPANY, A CORPORATION OF PENNSYLVANIA.

COIL MOUNTING.

Application filed April 15, 1925. Serial No. 23,297.

This invention relates to inductors of the type used with high-frequency currents. More particularly, it relates to the means of securing such inductors in place.

It is an object of this invention to provide a support and fastening means for a coil of the basket-weave type which can be rapidly and easily assembled and which is constructed of inexpensive parts.

It is a further object of this invention to provide a mounting for a coil of this type which shall hold the coil firmly in place and shall accurately position the coil in the apparatus of which it forms a part.

Other objects of the invention and details of construction will be clear from the following detailed description and accompanying drawings in which:

Figure 1 is a plan view of a preferred form of my invention;

Fig. 2 is an end elevation of the form illustrated in Fig. 1;

Fig. 3 is a detail plan of a supporting strip; and

Fig. 4 is a perspective view of a preferred form of supporting frame.

Referring to the drawings, a coil 1 may be of the type known as a basket-weave coil. Such coils are wound upon a form consisting of a number of parallel pins or rods.

The winding is made by passing the wire outside of one pin, inside of several pins, outside of the next pin, then inside of the same number of pins as before, and repeating.

The number of pins concerned in a single step of this winding is not a divisor of the total number of pins. Consequently, the second turn of the winding passes outside of different pins from the first turn. The successive turns are, therefore, staggered with relation to one another and the wire, where it passes one side of any given pin, is spaced from the wire of other turns on the same side of the same pin.

A consequence of this method of winding is that the wire forms a series of cells, parallel with the axis of the coil, a cell around each pin. When the coil is removed from the pins, these cells constitute openings, each extending through the coil from one end face to the other.

Strips of insulating material 4 are provided, each having a shank 5 and a head 6. Each strip has a shoulder 7 at the junction

of the shank 5 and the head 6. The width 55 of the shank 5 is sufficient to occupy a cell from wall to wall. The width of the head 6 is such that the shoulder 7 extends beyond the wall of the cell, enabling the shoulder to abut against the end surface of the coil. 60

The strips 4 are inserted into the coil, as best shown in Fig. 1. The left-hand strip 8 in this figure is introduced from the upper end of the coil. Consequently, the shoulder of its head 6 comes against the upper 65 end of the coil and its shank 5 extends beyond the lower end of the coil. A strip 9 of the same size and shape is inserted into the same cell from the lower end of the coil. Its head 10, therefore, provides a shoulder 70 11 contacting the lower edge of the coil. The shank 12 of this strip extends above the upper edge of the coil.

The strip 9 is farther from the axis of the coil than the strip 8. The two strips have 75 sufficient thickness to occupy all the distance, radially of the coil, which the cell affords for strips of the width of the shank 5. The edges of the shank 5 of the strip 9 are thereby brought into close contact with the outer 80 walls of the cell, and the face of the inner strip 8 contacts with the nearly flat inner wall of the cell.

At the right-hand side of Fig. 1 a similar pair of strips are shown inserted in the opposite order, whereby the head 13 of the inner strip is adjacent to the lower edge of the coil and the head 14 of the outer strip is adjacent to the upper edge of the coil.

When the strips are thus inserted, the width of the shanks prevents relative motion between any strip and the coil, except lengthwise of the strip. The two heads, one on each strip, prevent motion of the coil lengthwise of the strips, because the strips cannot move relative to each other for reasons explained below. In addition, the strips and the coil may, if desired, be held together by varnish or any other suitable binding material.

At the end of the head 6 opposite the shank 4, each strip has a tongue 15 by means of which the whole structure including the coil and strips may be mounted in any suitable brackets.

Two brackets 16 and 17, best shown in Fig. 4, are provided. These are mounted upon any suitable support 18, preferably of

insulating material. Openings 19 are provided in the brackets 16 and 17 to receive the tongues 15. Although these openings are illustrated as circular, it will be evident that 5 oblique, rectangular openings may be used when the brackets are intended for standardized coils, such as would be used in quantity production methods.

In the assembly of the device, the coil is 10 first wound upon pins and removed therefrom as already described, the strips are then inserted and, if desired, cemented into place. One of the brackets is then secured to the base 18 and the coil is put into position 15 with the tongues 15 at one end and the ends of the shanks at the same end extending through the openings 19 of said bracket. The other bracket is then placed with the openings 19 embracing the remaining 20 tongues 15 and the ends of the other shanks. The latter bracket is then secured to the base 18.

The coil and mounting constitute a unitary structure, the assembly of which is easy, 25 calls for no skilled labor and may be rapidly performed. The mounting is light and rigid and introduces a minimum of losses.

Although the specific description and illustration has been made with reference to a 30 coil wound outside one pin and inside several pins, obviously the same method of mounting may be applied to windings which pass outside of several pins and inside of others. Windings made in this way do not 35 produce a coil of the ribbed appearance which the coil illustrated possesses, but they have cellular prismatic openings extending lengthwise therethrough which may be used for the method of mounting disclosed herein. 40 Other modifications of the structure will readily occur to those skilled in the art and it is not intended that the specific description shall constitute a limitation. No limitation is intended except such as are required 45 by the prior art or stated in the accompanying claims.

I claim as my invention:

1. In a coil supporting device, a pair of 50 shouldered members positioned with their shoulders in opposite directions, and a coil supported on said members intermediate said shoulders.

2. In combination a cellular coil, supporting strips extending through one of the cells 55 thereof, each of said strips having shoulders,

the shoulders being at opposite extremities of the cell, whereby movement of the coil axially of the strips is prevented.

3. In combination, a cellular coil, a supporting strip for said coil, said strip having 60 a shank of a width approximately equal to the interior width of a cell of said coil, an enlarged portion on said strip and shoulders on said strip at the junction of said enlarged portion having a width greater than the 65 width of a cell.

4. In combination, a cellular coil, a supporting strip for said coil, said strip having a shank of a width approximately equal to the interior width of a cell of said coil, an 70 enlarged portion on said strip, shoulders on said strip at the junction of said enlarged portion having a width greater than the width of a cell, a tennon providing shoulders at the opposite end of said enlarged portion 75 and a recessed member cooperating with said tennon for supporting said coil.

5. In a coil support, a base, a pair of 80 brackets mounted on said base, coil-supporting members extending between said brackets, a cellular coil through which said coil supporting members extend, and shoulders on the respective coil supporting members, said shoulders engaging opposite ends of said coil.

6. In combination, a cellular coil having its turns arranged to alternately pass exteriorly and interiorly of a different number 85 of cellular spaces as the turns advance around the coil, and a pair of oppositely shouldered insulated supporting members arranged in one of said cellular spaces, whereby axial movements of the coil are prevented by the shoulder.

7. A coil-supporting device comprising in 90 combination a base-member provided with a pair of resilient uprights, a pair of relatively rigid elements supported in parallel relation by said uprights, means carried by each of said elements whereby one of said uprights 100 may exert pressure thereon longitudinally thereof, and additional means carried by each of said elements whereby said pressure may be transmitted to opposite portions of a coil carried by said elements. 105

In testimony whereof, I have hereunto subscribed my name this 6th day of April, 1925.

PAUL M. HENGSTENBERG.
